US00D842323S

(12) **United States Design Patent** (10) Patent No.: **US D842,323 S**
St. Arnaud et al. (45) Date of Patent: **** Mar. 5, 2019**

(54) **DISPLAY SCREEN OR PORTION THEREOF WITH GRAPHICAL USER INTERFACE AND COMPUTER ICONS**

(71) Applicant: **ROCHE DIAGNOSTICS OPERATIONS, INC.**, Indianapolis, IN (US)

(72) Inventors: **Luc St. Arnaud**, Meggen (CH); **Sandra Roth**, Rotkreuz (CH); **Olgu Guenal**, Pratteln (CH)

(73) Assignee: **Roche Diagnostics Operations, Inc.**, Indianapolis, IN (US)

(**) Term: **15 Years**

(21) Appl. No.: **29/625,080**

(22) Filed: **Nov. 7, 2017**

Related U.S. Application Data

(60) Division of application No. 29/570,279, filed on Jul. 7, 2016, now Pat. No. Des. 813,898, which is a continuation of application No. 29/493,840, filed on Jun. 13, 2014, now Pat. No. Des. 789,973.

CLAIM

The ornamental design for a display screen or a portion thereof with graphical user interface and computer icons, as shown and described.

DESCRIPTION

The sole FIGURE is a front view of a display screen or portion thereof with graphical user interface and computer icons showing our new design.

The broken lines in the FIGURE showing the display screen or portion thereof, text and other graphic elements form no part of the claimed design.

1 Claim, 1 Drawing Sheet
